UNITED STATES PATENT OFFICE.

EUSTACE GRAHAM SHEPPARD, OF LONDON, ENGLAND, ASSIGNOR OF ONE-HALF TO NERNST ELECTRIC LIGHT, LIMITED, OF LONDON, ENGLAND.

ELECTRIC-INCANDESCENT-LAMP HOLDER.

SPECIFICATION forming part of Letters Patent No. 701,949, dated June 10, 1902.

Application filed December 11, 1900. Serial No. 39,470. (No model.)

To all whom it may concern:

Be it known that I, EUSTACE GRAHAM SHEPPARD, electrician, a subject of the Queen of Great Britain and Ireland, residing at 82 Victoria street, Westminster, London, S. W., England, have invented certain new and useful Improvements in Electric-Incandescent-Lamp Holders, (for which I have made application for patent in Great Britain, No. 9,982, dated May 30, 1900, and in Germany, dated November 26, 1900,) of which the following is a specification.

My invention relates to detachable electric lamp or filament holders where three contacts require to be made in a reliable and simple manner and is especially applicable for use in "Nernst" lamps. In such lamps it becomes advantageous to make provision for the replacement of the worn-out filaments when required in an easy and simple manner. This involves the making of three contacts in such a way that it is not possible for the consumer to insert the holder in a wrong position.

My invention consists in providing three contact-pieces, one in or near the center of the lamp-holder and the others on opposite sides of that, but at different radial distances from the center, such that when corresponding contact-pieces similarly arranged on an insulating bridge-piece carrying the filament are placed into engagement with the first set of contact-pieces it is only possible for them to engage to close the electric circuit in one way—that is, only the proper terminals can touch or engage with one another. The engagement which takes place between the terminals is such that they become mechanically locked with a positive pressure, insuring electric contact at all three points.

Referring now to the accompanying sheet of drawings, Figure 1 is a central section of one modification of my improved lamp-holder applied to a Nernst lamp, which is represented in diagram. Fig. 2 is a side elevation of the same without the Nernst lamp. Figs. 3 and 4 are front elevations showing other modifications of the holder, and Fig. 5 is a front elevation of a fourth modification.

The same letters of reference are used to

indicate similar parts in different figures of the drawings.

In carrying my invention into effect, as illustrated in Figs. 1 and 2, I provide on the permanent base *a* three contact-pillars *b*, *c*, and *d*, situated along a diametric line across the base, the pillar *b* placed at or near the center and the pillars *c* and *d* on opposite sides of, but at different distances from, the pillar *b*. The pillar *b* I provide with a spring-pressed plunger *e*, and the pillars *c* and *d* I provide with hooks *f*, facing in opposite directions. In an insulating bridge-piece *g*, carrying the filament *n* and other parts of a Nernst lamp, as indicated in Fig. 1, I provide three terminals or contact-pieces *h*, *i*, and *j*, passing through it and situated in the said bridge-piece in positions corresponding to those of *b*, *c*, and *d* in the permanent base *a*. The two terminals or contact-pieces *i* and *j* are formed with eyes *k*, adapted to engage with the hooked terminals *c* and *d*.

One end of the terminal or contact-piece *h* forms the bottom of a socket *l*, into which the plunger *e* of the contact-pillar *b* is adapted to fit, so that a spring-pressed contact may be made at the bottom of the socket. The socket *l* is formed, preferably, of insulating material.

To make the electrical connection between the contacts *b*, *c*, and *d* on the base *a* and the contacts *h*, *i*, and *j* on the bridge-piece *g*, the latter is brought near to the base, with the spring-pressed plunger *e* passing into the socket *l*. The bridge-piece *g* is then pressed toward the base *a*, pushing back the plunger *e* till the eyes *k* come into the same plane as the hooks *f*. The bridge-piece *g* is then turned around till the hooks *f* project through the eyes *k*, when it is released, and the spring *m* of the plunger *e* pushes the bridge-piece away from the base *a* and causes the hooks and eyes to engage and make good electric contacts.

The contact-pillars *c* and *d* may, if desired, have their hooks *f* both facing in the same direction, in which case when the before-described connection is being effected the bridge-piece *g* would be pressed toward the base *a* at a slight angle and straightened to

pass the eyes *k* on to the hooks *f*, or the said contact-pillars may each be provided with double hooks facing both ways, either outward, as shown in Fig. 3, or inward, as shown 5 in Fig. 4, so that the bridge-piece *g* can be hooked to the base *a* by giving it a turn in either a right or left hand direction.

It will be obvious that various modifications may be made without departing from my invention—for example, as shown in Fig. 5, the outer terminals or contact-pieces might be provided with spring-pressed plungers *e* and the center one formed with a hook *f*, adapted to engage with an eye *k* on the corresponding terminal of the bridge-piece *g*.

Having now described my invention, what I claim as new, and desire to secure by Letters Patent, is—

1. In an electric-incandescent-lamp holder 20 the combination with two separable members of two hook-and-eye electric contacts coupling the members together and limiting the distance which they can move apart, and eccentrically arranged between them, a spring-pressed electric contact forcing the said members apart substantially as set forth.

2. In an electric-incandescent-lamp holder the combination with two separable members of a hook-and-eye electric contact coupling the members together and limiting the distance which they can move apart, of a spring-pressed contact-plunger on one member, a socket on the other member and a contact for the plunger within the socket substantially as set forth. 30

3. In an electric-incandescent-lamp holder, two separable members, a set of three contacts on each member one of the contacts in each set being axially arranged and spring-pressed, and the remaining two contacts on one member situated at unequal distances from the axial contact and consisting of double hooks, for engagement with eye-contacts similarly situated on the other member, substantially as set forth. 40

In witness whereof I have hereunto set my hand in presence of two witnesses.

EUSTACE GRAHAM SHEPPARD.
